UNITED STATES PATENT OFFICE.

WILLIAM E. FICKLEN, OF NEW YORK, N. Y.

PAVEMENT AND THE LIKE.

1,098,433.

Specification of Letters Patent.

Patented June 2, 1914.

Continuation of application Serial No. 633,353, filed June 15, 1911. This application filed October 12, 1912.
Serial No. 725,393.

To all whom it may concern:

Be it known that I, WILLIAM E. FICKLEN, a citizen of the United States, residing in the borough of Brooklyn, city of New York, county and State of New York, have invented certain new and useful Improvements in Pavements and the like, of which the following is a specification.

My invention relates to improvements in pavements and the like.

More specifically, the invention has to do with concrete pavements, whether the cement forming part of the same be hydraulic, bituminous or of other character; and the invention is directed to the strengthening, hardening and reinforcing of the pavement, and particularly of the wearing surface thereof.

The invention is especially applicable to curb and gutter edges, expansion joint edges, and to cross walks and all other surfaces subjected to hard wear and rough usage.

It is also applicable for building purposes, sewer piping and other structures where strength and toughness are important.

Briefly, the invention consists in mixing with, or otherwise introducing into, concrete, asphalt or other structural material, a quantity of rust-proof metal pieces of predetermined shape, thickness and size. The size and shape of the metal is determined by several considerations presently to appear. In pavements, the metal may be mixed with the material forming the surfacing layer before the latter is laid, or it may be introduced into the surface of that material after the same has been flooded, or otherwise placed. Similarly, when using the metal in edgings for curbs, gutters, expansion joints, and the like, the metal may be mixed with the concrete or other unset material to form the edging material before the latter is laid, or it may be introduced before the material has set or hardened, but after it has been laid.

The metal when applied as hereinafter described has many important functions. In pavements, it renders the surface, for all practical purposes, as hard and wear-resisting as would be a surface entirely of metal, without, however, making the pavement noisy or slippery. It acts as a true reinforcement, in that, by reason of the character of the metal pieces, and of the manner of inserting the same, they provide the tensile and compressive strength necessary to resist

expansion and contraction, so that creeping, cracking, and folding of concrete and asphalt surfacing layers may be practically eliminated. The metal prevents hydraulic concrete from chipping and "dusting", and prevents any paving material from disintegrating and sinking. The elimination of "dusting" is of large importance in the application of the invention to factory and other floors, since the dust and crumpling incident to such floors, particularly when made of hydraulic concrete, has been the cause of injury to the machinery and fabrics and other articles within the building. By reason of the added strength of the material due to the metal, the thickness of surfacing layers or other bodies of concrete, whether hydraulic, bituminous or asphaltic, may be greatly reduced, and a large saving thus effected. As applied to asphalt and bituminous pavements, mutilation of the pavement in hot weather, by the sinking of horses' hoofs and wheel tires into the same, is prevented.

In the present invention as applied to pavements, the metal pieces are shown so shaped that each lies in more than one plane. For this reason, any piece of metal presented to traffic will always have a portion thereof extending down into the structure to serve as an anchorage for the metal. I have also prescribed a size of from $\frac{1}{4}$ " to $1\frac{1}{2}$ " as the preferable and best size for this metal. If of larger size, there would be a liability of the metal being teetered and displaced when struck at one end by a hoof or tire.

The invention and the various applications of the same will more fully appear from the accompanying drawings, in which—

Figure 1 is a view in perspective of a cross sectional strip of a roadway having a top or wearing surface containing as an ingredient thereof metal pieces made and applied in accordance with the present invention. Fig. 2 is a view similar to Fig. 1, except that the metal, instead of being applied to the entire wearing surface, is applied only at the curb edges and expansion joints. Figs. 3 to 9, inclusive, show various forms of the metal pieces, in all of which figures the metal is shown so formed as to lie in more than one plane.

Referring to Fig. 1, the body of the pavement is shown as of any suitable mixture of stone and hydraulic cement or asphalt.

The surface or wearing layer 2 of the pavement contains as a component thereof a quantity of metal pieces 3, shown as of ring shape, but which may be of any suitable shape. The wearing layer in Fig. 1 is extended over the entire road surface, and over the gutters and curbs of the sidewalks. The pavement is preferably provided with expansion joints, as shown at 4; and the wearing layer 2 is of sufficient depth to provide a metal protection for some distance down the sides of the joints, so that chipping cannot take place at these joints. The metal in the layer 2 also serves to prevent chipping at the curb edges 5. As heretofore indicated, the material of the wearing layer 2 may have the metal 3 mixed therein before the same is applied to the roadway, or the metal may be scattered on the surface, and rolled or otherwise pressed into the wearing surface before the latter has completely set or hardened. The wearing surface 2 may be of hydraulic or similar cement; or, it may be an asphalt mixture. The functions of the metal have been heretofore set forth.

In the modification of the invention shown in Fig. 2, the metal mixture 6 is shown as applied only at the expansion joints 4, and at the curb edges 5. The rest of the roadway may be of any suitable hydraulic or other cement, or concrete, or may be of an asphalt mixture. It may or may not be built in several layers.

In Fig. 3, the metal piece 7 is shown as a strip with a hook 8 at each end, and bent at 9 near the center, so that it will be in more than one plane when in place in the pavement.

The member 10 shown in Fig. 4 is elliptical in shape, and is bent at 11, so that the two halves are in different planes.

Fig. 5 shows a metal piece 12 in the form of a chain link with the ends 13 turned in opposite directions out of the plane of the central portion 14.

The metal 15 of Fig. 6 resembles a staple, but is bent at 16 to throw the ends of the prongs out of the plane of the rest of the piece.

In Fig. 7 there is shown a piece of metal 17 hooked at both ends 18, and bent at 19.

The metal 20 of Fig. 8 is in somewhat the form of a figure "8" with portions thereof crossing each other in different planes at 21.

Fig. 9 shows a metal member 22 in the form of a spiral.

Many other forms of metal might be adopted; and these metal pieces should preferably be of size between $\frac{1}{4}$ " and $1\frac{1}{2}$ " in the line of their greatest dimensions. The size of the metal will be largely determined by the size of the other coarse ingredients of the wearing material, where such other coarse ingredients are present.

The metal mixture, in addition to the uses specifically mentioned, is adapted to a vast variety of uses. Its use in building constructions will be obvious. Pillars, posts, ties, boats, heavy piping, conduits, dams and many other structures may be formed in whole or in part of the metal mixture. In fact it should be useful wherever concrete may be used, and particularly wherever added strength or hardness is desired.

This case is a continuation of my application Serial No. 633,353, filed June 15, 1911, for pavements and the like, is so far as the subject matter of the two cases is the same.

What I claim is:

1. A concrete block for paving and the like, having a mass of metallic slugs or sleeves embodied therein along the border thereof at its upper surface.
2. An edging for pavements, crosswalks, curbs and other structures, consisting of hydraulic cement concrete or the like, with a mass of small rustproof metal elements of predetermined size and thickness embodied therein and indiscriminately positioned therein in relation to each other.
3. An edging for pavements, crosswalks, curbs and other structures, consisting of hydraulic cement concrete with a mass of small metal elements of predetermined size and thickness embedded therein and indiscriminately positioned therein with relation to each other.
4. A concrete mixture of the class described, consisting of a suitable concrete, filler, and cement, having intimately mixed therewith a mass of metal strips, rods or wires, each of which is fashioned into a shape of tortuous configuration, wholly curved, wholly angular, or a combination of both, the axis of each lying in separate planes from the plane upon which it rests.
5. A pavement wearing surface consisting of a paving mixture, and a mass of metal elements intimately mixed therewith, each of said strips fashioned into a curved or angular shape of tortuous configuration not exceeding two inches in its greatest dimension, the body of each shape extending wholly away from its plane of rest.
6. An article of manufacture for the purpose described, consisting of an elongated metal strip so shaped that its axis lies in several planes, each of which is separate from the plane of its supporting point when the body is in a position of rest.
7. An article of manufacture for the purpose described consisting of an elongated metal strip fashioned into a shape of tortuous configuration, wholly curved or wholly angular or a combination of both, whereby each individual shape will lie wholly above the plane upon which it rests.
8. An article of manufacture for the purpose described consisting of an elongated

metal strip fashioned into a curved or angular shape of tortuous configuration, not exceeding two inches in its greatest dimension, whereby the body of each shape is bounded by two parallel planes.

9. A paving mixture consisting of a suitable aggregate, filler and cement intermingled with a mass of metal rods or wires, each of which is fashioned into shapes of tortuous configurations, wholly curved, wholly angular, or a combination of both, whereby the body of each lies separated from its plane of rest.

10. A concrete block for paving and the like having a mass of miniature metallic slugs or shapes embodied therein along the border thereof at its upper surface in sufficient number to constitute a corner protec-

tor, said slugs or shapes being also disposed across the upper surface of the block. 20

11. A wearing surface for pavements, crosswalks, curbs and other structures consisting of hydraulic cement, concrete or the like, with a mass of small elements of predetermined size and thickness embodied therein at the upper surface and indiscriminately positioned therein in relation to each other, a sufficient number of said elements being disposed along the edging to constitute a corner protector. 25 30

Signed by me at New York city, N. Y., this 10th day of October, 1912.

WILLIAM E. FICKLEN.
